UNITED STATES PATENT OFFICE.

HOWARD CARLISLE, OF LEESBURG, NEW JERSEY.

TRAIN CONTROL.

1,277,854.

Specification of Letters Patent. Patented Sept. 3, 1918.

Application filed January 8, 1916. Serial No. 71,006.

To all whom it may concern:

Be it known that I, HOWARD CARLISLE, a citizen of the United States, residing at Leesburg, in the State of New Jersey, have 5 invented new and useful Improvements in Train Controls, of which the following is a specification.

This invention relates to train controlling mechanism, and an object thereof is to provide 10 a system for automatically controlling and stopping the movement of a train, or other vehicle, when there is a dangerous condition preceding the same.

The invention provides novel means 15 whereby two or more trains upon entering the same block, or other specified section of trackway, will be automatically stopped, without manual assistance and regardless of their direction of movement.

20 The invention consists of electrically operated mechanism carried upon a train, which is operated upon the presence of another train within the same block, the mechanism being of a character to simultaneously 25 apply the brakes of the train and to shut off its source of propelling power upon the closing of a track circuit.

Other features will be in part obvious and in part pointed out hereinafter.

30 The invention accordingly consists in the features of construction, combination of elements, and arrangement of parts which will be exemplified in the construction herein described, and the scope of the application of 35 which will be indicated in the following claim.

In the accompanying drawings, where is shown one of the various possible embodiments of the invention,

40 Figure 1 is a diagrammatic view of the present invention illustrating particularly the electrical features thereof;

Fig. 2 is a vertical sectional view of the vehicle carried valve structure,

45 Fig. 3 is a sectional view of one of the contact shoes;

Fig. 4 is a detail perspective view of the port controlling valve;

Fig. 5 is a transverse sectional view on 50 the line 5—5 of Fig. 2;

Fig. 6 is a horizontal sectional view on the line 6—6 of Fig. 2;

Fig. 7 is a similar view on the line 7—7 of Fig. 2.

55 Corresponding and like parts are referred

to in the following description, and indicated in all of the views of the drawing by the same reference characters.

The numeral 5 designates a standard form of trackway, over which trains or other vehicles may be operated, and preferably located centrally of the tracks are circuit forming rails 6, which are insulated at spaced points to establish "blocks" or communicating circuits 7. The rails 6 extend 65 in parallelism with the trackway 5 and are positioned in such relation that the blocks or circuits 7 will overlap, as clearly indicated in Fig. 1.

Carried upon a locomotive or other vehicle, are contact shoes 8, located in juxtaposition and normally pressed downwardly by springs 9, to insure a positive contact between the shoes and the circuit rails 6. Connected with the shoes 8 are conductors 10 75 which extend to a solenoid 11, the latter, under certain conditions, receiving its source of energy from a series of storage batteries, 12, to which current is applied by an electrical generator 13, operated by any suitable 80 mechanism. A conductor 14 is grounded upon the locomotive, thereby providing a normally open circuit, caused by the lack of communication between the rails 6 and the trackway 5. However, upon the entrance of a second train into a block 7, the gap between the rails and the trackway will be closed, thereby completing the circuit and energizing the solenoid 11. It will be 85 evident that normally the circuit is open, permitting the unhindered movement of the locomotive, as will be presently disclosed, but upon the entrance of a second train into the block 7 the circuit will be closed to operate mechanism for stopping both trains. 90 The blocks 7 are to be varied in length and are preferably shortened to conform to the requirements of relatively congested yards or stations, but are of substantially 95 greater length when used upon less frequented stretches of trackway.

The locomotive stopping mechanism consists of a unitary valve structure, designed, when operated, to apply the air-brakes of a locomotive and to simultaneously close the 105 supply of steam to the driving cylinders thereof. To this end the valve structure comprises a series of cooperating cylinders in which are positioned reciprocating piston shaped valves. One of the cylinders, indi- 110

cated by the numeral 19, is provided with a normally closed air inlet port 19, from which a pipe or duct 20 extends to an air reservoir or tank 21. Slidably positioned within the cylinder 18 is a port controlling valve 22, formed with a horizontally extending air inlet port 23 and an S shaped exhaust or outlet port 24. The valve 22 normally covers the port 19 so as to prevent the passage 10 of air therethrough. The valve is also provided with an operating rod 25, extending out of the cylinder 18 through a stuffing box 26 formed in one end thereof, and said valve is retained in the upper portion of the 15 cylinder 18 by providing the rod 25 with a fixed collar 27, formed with arms 28 to which coiled springs 29 are attached, the opposite extremity of the springs being secured to a stationary point upon the outer 20 side of the cylinder 18, so that the tension exerted thereby will retain the valve 22 in its elevated position within the cylinder 18. An elastic buffer 30^a is interposed between the valve and the upper head of said 25 cylinder to eliminate jar or undue friction between the two members. An outlet opening 31 is formed in the cylinder 18 and normally communicates with one extremity of the port 24 and its function will be presently 30 disclosed.

The rod 25 extends downwardly below the cylinder 18 and co-operates with the solenoid or magnet 11, the extremity of the rod forming the core of the solenoid, so that when 35 the latter is energized, by previously described conditions, a downward pull will be imparted to the rod 25 and its connected valve 22. The valve 22 is then lowered to a point until the port 23 formed therein is 40 in registration with the air inlet port 20, permitting air to circulate freely through said port 23. Formed in horizontal alignment with the port 23, in the wall of the cylinder 18, is a port 30 which opens into 45 a horizontally extending cylinder 31 provided with a sliding valve 32 of similar design to the valve 22.

The cylinder 31 is also provided with an air inlet port 33, to which a pipe 34 is connected, the opposite end of said pipe communicating with the reservoir 21. Graduated openings 35 are formed in the walls of the cylinder 31 adjacent the port 33 and similar openings 36 are formed in the opposite side of said cylinder adjacent an outlet port 37. The port or openings 35 and 36, however, are normally closed by the body of the valve 32 which prevents the passage of air from the reservoir 21 to the outlet pipe 60 37, the latter leading to the brakes, (not shown) so that when air is admitted therethrough the brakes will be applied. It will now be seen that when the port 23 of the valve 22 is in alignment with the pipe 20, air 65 will be admitted into the cylinder 31, result-

ing in the forward movement of the valve 32. As the valve moves forwardly a vertical air passage 38 formed therein registers with the smaller of the openings 35 thereby admitting a restricted amount of 70 air into the pipe 37, this volume of air is increased as the valve continues to move forwardly until the air passage 36 is in direct registration with the largest of the openings 35 and 36 which permits an unrestricted 75 flow of air to pass from the reservoir 21 into the pipe 37. The graduated openings 35 and 36 are designed to permit of a gradual application of the brakes controlling the movement of the train. 80

A third cylinder 39 is connected with the cylinder 31 in horizontal alignment therewith and is provided with a slidable piston or valve 40 which is connected with valve 32 for synchronous movement. A steam supply pipe 41 is threaded into the cylinder 39 and through which the supply of steam from the steam dome of the locomotive to the driving cylinders (not shown) is transmitted. It is evident that upon the movement of the valve 32 the piston 40 is simultaneously moved into a position blocking the passage of steam or other operating fluid, through the pipe 41, resulting, of course, in the stopping of the locomotive. 90 By this construction the brakes are applied in such a gradual manner as to reduce the jar or shock occasioned from applying said brakes without discomfort to the occupants of a train and without any possibility of 95 wrecking the train, as might happen upon applying the brakes with full instantaneous pressure. The source of power of the locomotive will also be cut off, thus insuring the operation of the device, and effectually 100 bringing the train to a standstill. 105

After the train has been stopped the circuit may be broken by operating the hand switch 43' which permits the valve 22 in the cylinder 18 to be restored to its normal position by the action of the coiled springs 29, thereby stopping the flow of air through the port 23 into the cylinder 31. In order to restore the valves 32 and 40 to a normal position to permit the operation of the locomotive, a helical spring 43 is positioned around a rod 44, connecting said valves 33 and 40, and is confined between the forward end of the valve 32 and the head of the cylinder 31. When the valve 32 is in an open 110 position, the spring is under tension. However, when the air pressure is taken off said valve the force exerted by the spring restores the valve to its normal retracted position, thereby restoring communication through 115 the pipe 41 and shutting off the air pressure upon the brakes, as will be obvious to those skilled in the art. 120

It will thus be seen that there is provided 125 mechanism in which the objects of the pres- 130

ent invention are achieved and all the advantageous features above mentioned are, among others, present. The apparatus is positive in action, of few parts, and simple construction. The parts are so formed that the device can be readily adapted to locomotives of the present design and will not interfere with an engineer while the latter is performing his duties, as the device is so positioned as to be out of the way of all operating levers. It is to be understood that the arrangement of the various parts shown and described, in this specification, has been disclosed for purposes of explanation and description only and that said parts may be so positioned as practice may determine to be the most advantageous.

As many changes could be made in the above construction and many apparently widely different embodiments of this invention could be made without departing from the scope thereof, it is intended that all matter contained in the above description or shown in the accompanying drawing shall

be interpreted as illustrative and not in a 25 limiting sense.

Having thus described my invention, I claim:—

In a train controlling mechanism adapted to be used for supplying air gradually to 30 the brakes, a cylinder provided at its opposite sides with openings which gradually increase in size, a spring pressed valve located in the cylinder and having a passageway adapted to register with the said openings 35 successively, and having an area in transverse section equal to the area of the largest opening, electric controlled means for admitting air into the cylinder to move the valve against the tension of the spring, said 40 means being normally held in a closed position, means for leading air into the cylinder through the openings and means for leading the air from the cylinder to the 45 brakes.

In testimony whereof I affix my signature.

HOWARD CARLISLE.
